LJUNGSTRÖMS ANGTURBIN, OF FINSPONG, SWEDEN.

SHIP-TURBINE.

1,205,459.

Specification of Letters Patent. Patented Nov. 21, 1916.

Application filed September 11, 1915. Serial No. 50,242.

To all whom it may concern:

Be it known that I, FREDRIK LJUNGSTRÖM, engineer, a subject of the King of Sweden, residing at Finspong, Sweden, have 5 invented certain new and useful Improvements in or Relating to Ship-Turbines, of which the following is a specification.

In ship turbines where the propeller shafts are driven through the agency of spur 10 gearing it is a matter of the greatest importance that the placing of the turbine, condenser and gearing should be effected in such a manner as to allow the disposable space to be made use of in the most efficient way.

The present invention refers to turbines of the double rotation type and has for its object to place the three said parts so that they occupy an exceedingly small space. 20 The turbine is in effecting this given so high a position that the condenser may be placed under the same, besides which the condenser and the turbine casing are placed between the two gearings from the two turbine 25 shafts. The condenser or the inlet of the same is preferably passed at this point by the intermediate shaft joining the two spur wheels mounted on each side of the condenser.

20 In the accompanying drawing, Figure 1 represents a side elevation of a turbine embodying my invention; and Fig. 2 represents a longitudinal, central, vertical section of the same.

25 *a* is the turbine casing of a double rotation turbine and *b b'* are the two shafts of the same, supporting pinions, meshing with a greater pinion, inclosed in the wheel casings *c c'* and arranged under the shafts *b b'* and the wheels mounted upon the latter.

The number of wheels of one gearing is odd, that of the other even, whereby the common shaft *d* will be driven in the same direction by the two turbine shafts *b* and *b'*. Under the turbine casing *a* the condenser *e* is arranged between the two greater spur wheels, mounted in the wheel casing *c c'* and arranged in such a way that its longitudinal axis is perpendicular to the turbine shafts *b b'* or the intermediate shaft *d*. The latter 45 passes through the inlet pipe *f*, joining the turbine casing *a* to the condenser *e*. 50

Either the shaft may be the propeller shaft or there may if necessary be mounted a further gearing (or more) between this 55 shaft *g* and the propeller shaft *h*.

Claims:

1. In combination with a turbine-casing, a condenser mounted thereunder, a pair of turbine shafts, a third shaft driven by these 60 turbine shafts, and two sets of gearing between said turbine shafts and this third shaft, said sets of gearing being arranged with the condenser and turbine casing between them. 65

2. In combination with a turbine-casing, a condenser mounted thereunder, a pair of turbine shafts, a third shaft driven by these 70 turbine shafts and passing through a tubular part connected to said condenser, and two sets of gearing between said turbine shafts and this third shaft, said sets of gearing being arranged with the condenser and turbine-casing between them.

In testimony whereof I have affixed my 75 signature in presence of two witnesses.

FREDRIK LJUNGSTRÖM.
